Cornelius C. Billings
his ATTORNEY

UNITED STATES PATENT OFFICE.

LOUIS STEINBERGER, OF BROOKLYN, NEW YORK.

STRAIN INSULATOR.

Application filed September 23, 1921. Serial No. 502,658.

To all whom it may concern:

Be it known that I, LOUIS STEINBERGER, a citizen of the United States, and a resident of the borough of Brooklyn, city and State 5 of New York, have invented certain new and useful Improvements in Strain Insulators, of which the following is a specification.

This invention relates to insulators for 10 the support and insulation of electric conductors employed for many purposes such as wireless telegraphy and telephony and in various kinds of electric power transmission and especially constructed for use 15 in connection with currents of very high voltages and very high frequencies.

The particular object of my invention is 20 to improve the construction of such insulators, so as to render them proof not only against the destructive effects of high frequency currents, but also against the destructive 25 effects of lightning, and at the same time simplify the construction and decrease the cost thereof.

Another object is to provide an insulator 25 with arcing means, each member of which is situated upon the same side of the insulator body.

Another object is to so mount the arcing 30 members that they will not only be situated upon the same side of the insulator body, but are disposed directly opposite to each other.

Other objects will appear from the sub- 35 joined specification and claims.

Referring to the drawings in which the same reference character indicates the same part in the several views:

Fig. 1 is a cross section of an insulator 40 embodying my invention, portions of the construction being shown in elevation.

Fig. 2 is a section on line 2—2 of Fig. 1, with portions shown in elevation and other portions broken away.

Fig. 3 is a section on line 3—3 of Fig. 1. In the drawings, A is a body formed of 45 suitable insulating material, preferably that material known in the art as electrose. The body may be molded or constructed in any 50 preferred shape with the sole exception of the depression in one end thereof which will be hereinafter specifically described. Preferably the side of the body is provided with alternate grooves and flanges in order to 55 lengthen the creepage surface thereof and also to form watersheds. B is an integral

strain member molded to the insulator body, as shown, and C is a two-part strain member, one portion 10 of which is molded to the insulator body, as shown, and is thus 60 caused to interlock with the integral strain member B, the projecting ends 11 and 12 of the embedded portion 10 being screw-threaded, as shown.

The removable portion 20 of the strain 65 member C is constructed in the manner known in the art so that it may be readily secured to the embedded portion 10 of the strain member C. One end of the portion 20 is provided with a screwthreaded cavity 21 which engages with the screwthreaded end 11 of the portion 10. The screwthreaded end 22 of the portion 20 is placed opposite to the fixed projecting end 12 of the portion 10 and a screwthreaded nut n is caused to 70 engage the screwthreads of both parts 12 and 22 in order to hold the portion 20 of the strain member in place, which nut is run up into the screwthreads 22 clear of the screwthreads 12 when a disengagement 75 of these parts is desired.

A cavity D is formed in one of the ends of the insulator body A and the bottom of the cavity is so shaped that the strain member B is exposed to the atmosphere at 85 its central portion b. A screwthreaded cavity 15 is formed in the center of the exposed portion b of the strain member B and the screwthreaded shank 31 of the arcing member 30, which is provided with an 90 enlarged rounded head, engages said screwthreaded cavity 15 so that the arcing member 30 may be adjustably mounted upon the strain member B.

A bar or bridge portion E is provided 95 with a centrally depressed portion and it supports an opposing arcing member 40, the head of which is similar in shape and contour to that of the arcing member 30. The member 40 is secured to the centrally de- 100 pressed portion of the bar or bridge E by a screw bolt 42 engaging a screwthreaded cavity 43 therein. The ends of the bridge member E are provided with holes or openings 45 and 46 which fit respectively over 105 the projecting ends 12 and 11 of the part 10 of the strain member C and is held in place by the enlarged ends 21' of the member 20 and by the nut n, each of which engages the respective ends of the bridge member E 110 when the removable portion 20 is secured in place.

As will be readily understood from the above construction, the arcing members 30 and 40 are adjustably mounted in fixed relation to each other upon the same side of 5 the insulator body, each arcing member being secured to the respective strain members in the same axial line.

From the above description it will be seen that by nesting the arcing members so that 10 they will be situated opposite to each other upon one side only of the insulator, I have made a simple and compact construction as distinguished from those constructions provided with free projecting arms extending 15 over the insulating body when the arcing members are mounted one upon each side of that body.

Another benefit resulting from my construction over those which have extending 20 supporting arms is that the danger of accumulating dirt, twigs, hay or any other thing which may be blown upon the insulator is reduced to a minimum. Moreover, the danger of bending or breaking the projecting arcing member supporting arm is 25 obviated or greatly lessened.

As changes of construction could be made within the scope of my invention, it is intended that all matter contained in the 30 above description or shown in the accompanying drawings shall be interpreted as illustrative and not in a limiting sense.

Having now described my invention, what I claim as new and desire to secure by 35 Letters Patent is:

1. An insulator provided with a strain member secured to the body thereof, the inner end of said strain member being exposed to the atmosphere, and an arcing 40 member secured to the exposed portion of said inner end, a bridge member secured to the opposing strain member upon the same side of the insulator body and provided with an arcing member secured to the central 45 portion thereof.

2. An insulator provided with a strain member partially embedded therein, the inner part of said strain member being exposed to the atmosphere, an arcing member secured to the exposed portion of said strain member, a bridge portion rigidly but removably secured to the projecting portions of the opposing strain member, and a separate and independent arcing member secured to the central portion of said bridge member 55 and situated opposite to the said first mentioned arcing member in the line of the axis of the insulator, both arcing members being mounted on one side only of the insulator body.

3. An insulator having a body portion of insulating material, strain members partially embedded in the body portion both projecting from one side of the body portion, and arcing means consisting of members secured to the respective strain members upon the aforesaid side of the insulator body portion.

4. In an insulator, a body of insulating material provided with a cavity upon one face thereof, strain members secured to the body of insulating material, the inner portion of one of said strain members projecting into said cavity, an arcing member secured to said inner portion of the strain member, a bridge member extending across said cavity and secured to the other strain member, the bridge member having an arcing member secured to the central portion thereof and oppositely disposed to the first mentioned arcing member upon the same side of the insulator body.

In witness whereof, I have hereunto set my hand at the borough of Manhattan, city and State of New York, this 15 day of September, 1921.

LOUIS STEINBERGER.

In presence of—
ISABEL R. FLETCHER.
